US00D841673S

(12) **United States Design Patent** (10) **Patent No.:** **US D841,673 S**
Feit et al. (45) **Date of Patent:** **** Feb. 26, 2019**

(54) **DISPLAY SCREEN WITH GRAPHICAL USER INTERFACE**

(71) Applicant: **HONDA MOTOR CO., LTD.**,
Minato-ku, Tokyo (JP)

(72) Inventors: **Steven Feit**, Dublin, OH (US); **David Vanderburgh**, Dublin, OH (US); **Ross Miller**, Hilliard, OH (US); **Koo Ho Shin**, Huntington Beach, CA (US)

(73) Assignee: **HONDA MOTOR CO., LTD.**, Tokyo (JP)

(**) Term: **15 Years**

(21) Appl. No.: **29/590,076**

(22) Filed: **Jan. 6, 2017**

(51) LOC (11) Cl. **14-04**
(52) U.S. Cl.
USPC **D14/486**

(58) **Field of Classification Search**

USPC **D14/485-495**
CPC B60K 37/00; G06F 3/0482; H04N 1/00408
See application file for complete search history.

(57) **CLAIM**

The ornamental design for a display screen with graphical user interface, as shown and described.

DESCRIPTION

FIG. 1 is a front view of a display screen with graphical user interface showing a first embodiment of our new design; FIG. 2 is a front view of a display screen with graphical user interface showing a second embodiment of our new design; FIG. 3 is a front view of a display screen with graphical user interface showing a third embodiment of our new design; and,

FIG. 4 is a front view of a display screen with graphical user interface showing a fourth embodiment of our new design. The broken line showing the remainder of the display screen with graphical user interface is for environmental purposes only and forms no part of the claimed design.

1 Claim, 4 Drawing Sheets
